UNITED STATES PATENT OFFICE

HARVEY M. GERSMAN, OF CHICAGO, ILLINOIS

PRODUCTION OF EXPANDED-STEEL LOAD-BEARING MEMBERS

Application filed February 9, 1925. Serial No. 7,764.

This invention relates to the production of expanded steel load bearing members and more particularly to the production of such members in integral form from a rolled structural shape.

The principal objects of the invention are to provide a process of economical character by which a maximum output is achieved, to provide for a full measure of expansion without any liability of the tearing or fracturing of the product, and to secure an expanded beam of superior quality and physical characteristics.

With the above objects in view the process is principally characterized by the provision of a slotted blank heated to a degree at which the metal does not flow but may be stretched and shaped and by the stretching of the bar or strand portions prior to the relative outward movement or separation of the flanges or chord portions of the blank followed by such relative outward movement or separation and the simultaneous pressing back of the stretched bar or strand portions into the original plane of the web.

By proceeding in this manner the stretching of the bar or strand portions and the increase of the width of the blank are carried out in separate and successive operations with the results that the angles of the bar or strand portions during the stretching operation are most favorable to the integrity of the finished product and the subsequent increase in the width of the blank does not involve any stretching of the bar or strand portions but is merely a part of the operation of forming open work.

The process is also characterized by a preliminary deformation of the parts which are to be displaced during the stretching operation and in which the strand portions are included, this deformation being carried out in such a manner as to make each strand portion of the same thickness throughout its extent and being performed prior to the operation of stretching the strand portions in preparation for the formation of open work.

The above and other characterizing features of the process will be set forth as the description proceeds and will appear from

the accompanying drawings which illustrate apparatus by which the process may be practiced, the several steps in the evolution of the blank into the completed product, and a portion of the expanded beam produced by the process. The apparatus and the beam, however, although completely illustrated are not claimed in this application but form the subjects of my pending applications, Serial Nos. 10,349 and 7,765.

In said drawings:

Figure 1 is a side elevation showing, diagrammatically, apparatus by which the process may be practiced.

Figure 2 is a top plan view of the same.

Figure 3 is a cross section showing a preferred form of blank.

Figure 23 is a plan view of a portion of the 30 blank and an adjacent portion of the spreader conforming to the operation of Figure 22.

Figure 24 is a sectional view on the line 24—24 of Figure 23, this view also showing the lower portion of the second flattening 35 roll.

Figure 25 is a cross section on the line 25—25 of Figure 1, more particularly showing the operation of the third flattening roll.

Figure 26 is a plan view of a portion of the 40 blank and an adjacent portion of the spreader conforming to the operation of Figure 25.

Figure 27 is a sectional view on the line 27—27 of Figure 26, this view also showing the lower portion of the third flattening roll.

Figure 28 is a cross section on the line 28—28 of Figure 1, more particularly showing the operation of the fourth flattening roll.

Figure 29 is a plan view of a portion of the 50 blank and an adjacent portion of the spreader conforming to the operation of Figure 28.

Figure 30 is a sectional view on the line 30—30 of Figure 29, this view also showing the lower portion of the fourth flattening 55 roll.

Figure 31 is a cross section on the line 31—31 of Figure 1, more particularly showing the final flattening and delivery rolls.

Figure 32 is a plan view of a portion of the 60 completed beam.

Figure 33 is a sectional view on the line 33—33 of Figure 32.

Figure 34 is a plan view of the slotted blank 65 which is used for the production of a Warren truss.

Figure 35 is a perspective view of the same at the completion of the stretching of the strand portions.

Figure 36 is a plan view of the completed product in the form of a Warren truss. 70

Figure 37 is a sectional view on the line 37—37 of Figure 36.

Fig. 38 is a detailed view.

The process of the present invention is preferably practiced continuously and may be so 75 practiced in connection with the rolling of the blank. In such case the process starts with the blank as it comes from the rolling mill at a temperature below the flowing temperature but sufficiently high to enable parts of 80 the blank to be stretched, shaped and relocated, the steps of the process being all completed while the blank is within the permissible range, i. e., heated to cherry red.

The product in its form of greatest advantage and widest range of utility is conceived as an expanded beam of I cross section which is preferably fashioned as a lattice truss but may also be fashioned as a Warren truss. In 90 either case the blank delivered by the rolling mill and with which the process is started may be of regular I cross section.

The drawings illustrate in detail the production of a lattice truss and for most, if not all, practical purposes it will be sufficient if the struts of the completed beam have a single line of intermediate bonds representing points of intersection, the remaining bonds being the connections between the struts and the chords. The blank for such a beam will have three longitudinal rows of slits arranged in the manner and relation of the slits provided in the blanks from which diamond mesh lath, so called, is produced, that is to say with the slits of each row in symmetrically staggered or break-joint relation to the slits of the adjacent row or rows. While the blank for such a beam may, as stated, be of regular I cross section it is preferably of a modified original cross section which promotes the facility of the slitting operation, such a blank, as B, being shown in Figures 3 and 4 and being provided with parallel flanges 1 and a connecting web 2 which has a wide-angled V cross section that provides angularly related longitudinal web portions 2a and 2b. 100

The operations in the order of their performance are slitting the blank, unifying the thickness of the bar or strand portions and the intermediate bonds, stretching the bar or strand portions, and separating the flanges and pressing the stretched bar or strand portions and the intermediate bonds back into a single common plane. The several elements 110 of the apparatus by which these operations are carried out may, of course, be structurally varied. As diagrammatically shown, the apparatus includes slitting rolls 3 and 4, strand unifying or compensating rolls 5, strand 115 120 125 130 135

stretching rolls 6 and 7, strand flattening rolls 8, 9, 10, 11 and 12, the rolls 12 also serving as delivery rolls, a spreader 13 which is co-operative with the rolls 8, 9, 10 and 11, and feed rolls 14 which act on the flanges 1 and may be arranged as required or desirable, in some instances being mounted on the shafts of certain of the other rolls and in some instances being mounted on shafts specially provided therefor. The several shafts which carry the rolls above enumerated are indicated at 15 and are mounted in bearings for which housings 16 are provided, the shafts being positively driven from a line shaft (not shown) or otherwise suitably by gearing which is sufficiently indicated by the showing of a gear element 17 for each shaft.

The slitting rolls may be of any well known type. While the slitting may be performed in a single stage it is preferably performed in two successive stages, the first stage by the rolls 3 and the second stage by the rolls 4. In the first stage (Figures 5 and 6) the blank is formed with the central row of slits 100 and in the second stage (Figures 7, 8 and 9) with the outer rows of slits 101, these being located close to the web. The modified cross section of the blank is of advantage as will appear from Figures 5 and 7 in that the angle of the portions which are displaced during the slitting to the shearing edges is at no point greater than a right angle and this characteristic provides for greater facility in the slitting operation than is possible where, as in a blank of regular I form, certain portions of the web which would be displaced during the slitting operation would lie at an obtuse angle to the shearing edge. In the first stage of the slitting as effected by the rolls 3 the portion 2b is moved into a plane normal to and located centrally of the flanges 1 and parts of the portion 2a (being those parts which provide the intermediate bonds) are similarly displaced while the remaining parts of the portion 2a are held in their original plane and are thus severed from the adjacent parts of the portion 2b. In the second stage of the slitting as effected by the rollers 4 the parts of the portions 2a which during the first stage were held in their original plane are moved into the same plane as the portion 2b, that is to say a plane normal to and located centrally of the flanges 1, and from this common plane adjacent parts of both of the portions 2a and 2b are displaced into a common plane parallel to the plane from which the displacement started, the portions so displaced being thus severed from the web along lines parallel and adjacent to the flanges and leaving in the plane from which the displacement started those portions which provide the bonds between the struts and the chords, i. e., the outer lines of bonds, and if, as preferred, the outer lines of slits be slightly distant from the flanges also leaving chord por-

tions of the web. In Figures 8 and 9 the strand portions are indicated at 102, the portions which provide the intermediate bonds at 103, the portions which provide the bonds of the outer lines at 104 and the chord portions at 105.

The strand portions 102 and the intermediate bond providing portions 103 are, as above explained, displaced incident to the slitting operation in planes parallel to the planes of the outer bond providing portions 104 and the chord portions 105. In consequence of this displacement the length of the parts between successive portions 104, these parts being two strand portions 102 and an intermediate bond providing portion 103 located between them, is greater than the length which these parts had prior to their displacement, that is to say prior to the cutting of the outer slits 101. It follows that as an incident of the slitting operation there is some stretching of the metal of the displaced portions. This stretching occurs in the parts by which the displaced portions are connected to the outer bond providing portions 104, these parts being shown in Figure 9 at 102a and being terminal parts of the strand portions 102 which extend diagonally from the straight parts of such strand portions to the portions 104. Thus the parts 102a due to their stretching are of somewhat less thickness than the parts 104 and the straight parts of the strand portions 102. It is desirable, however, that the displaced parts be of equal thickness throughout their extent since, otherwise, the resultant strands would not only be of unequal thickness at different points but the parts stretched during the slitting operation would be further attenuated during the ordered stretching operation, offering as they do less resistance to the stretching forces than the remaining parts, and would therefore be a source of weakness in the finished beam. I therefore provide for compensating the stretch of the parts 102a by making all parts of the bond providing portions 103 and the strand portions 102 of equal thickness, this end being best served by attenuating the intermediate bond providing portions 103 and the flat parts of the strand portions 102 prior to the ordered stretching operation whereby said flat parts and their connecting portions 103 are increased in overall length and are reduced to the same thickness as the connecting parts 102a. This operation is accomplished by a pair of unifying or compensating rolls 5, one acting on the blank from above and the other from below. The rolls 5 are formed with co-operating transverse corrugations which are shaped and arranged to deform the displaced portions of the blank into sinuous outline as shown in Figures 11 and 12, the parts 102a being included in the sinuous curve at any point of which the metal is of the same thick- 125

ness as at any other point. The general form and arrangement of the rolls 5 is illustrated diagrammatically in Figure 1 and in greater detail in Figure 38. The transverse corrugations above mentioned are provided in co-operating series on the two rolls, the corrugations of each series being designed and arranged to produce the preliminary strand formation shown in Figure 12, and to avoid 10 any stretching of the panel point providing portions of the blank. It follows that between the adjacent series of corrugations of each roll there will be breaks which constitute inactive areas, and it is obvious that in 15 producing the preliminary strand formation shown in Figure 12, a series of corrugations on one roll will intermatch with and cooperate with a corresponding series of corrugations on the other roll, and that the break 20 of one roll will register peripherally with the break of the other roll during the period when a panel point providing portion passes between the rolls. The result of the operation of the rolls formed and arranged in the 25 manner described is the formation shown in Figure 12, wherein those strand providing portions which are connected by an intermediate bond providing portion are, together with such bond providing portion, uniformly 30 preliminarily stretched. It is to be noted that the deformation of the strand portions is shown in Figures 11 and 12 on a somewhat exaggerated scale in order to promote clearness of illustration.

35 The stretching operation follows the operation of the compensating rolls and is preferably formed in more than one stage, two stages being provided for in the apparatus disclosed. The stretching operation is so 40 performed that the intermediate bond providing portions 103 are offset in paths at right angles to the mean longitudinal plane of the web with the result that the adjacent strand portions at opposite sides of the several slits 100 while remaining in parallel relation are stretched proportionately to the increase in the distance between their ends as measured by their points of connection with the respective bond providing portions 103 and 104. By proceeding in this manner the 45 bending of the strands where they join the bond providing portions is along transverse lines and the stretching forces are applied at right angles to these transverse bending lines with the result that there is no possibility of tearing. Various mechanical agencies may be employed for offsetting the bond providing portions 103 in order to stretch the strand portions 102. As shown in the drawings the means for this purpose consists of the rolls 6 and 7 which are provided with suitable teeth as shown. These rolls are arranged whereby their teeth enter the angle of the convolution of which the portion 103 50 provides the apex. As shown in Figure 12

this angle faces downward and the rolls 6 and 7 are accordingly arranged to engage the blank from below. The teeth of the roll 6 act in the first stage of the stretching operation and are therefore of less depth than the teeth of the roll 7 by which the stretching operation is completed. At the completion of the first stage of the stretching operation, as shown in Figure 15, the strand portions 102 have been straightened from the sinuous form which they had when the operation started and have been stretched to a partial extent. At the completion of the second stage of the stretching operation, as shown in Figure 18, the strand portions have been stretched to the degree which may have been determined upon and each stretched part which includes an intermediate bond providing portion and the strand portions thereby connected is displaced into substantial V-form. 70

75 The next step is the expansion of the blank into the completed structural section. This involves operations merely for the production of open work and does not involve any sensible stretching of any of the parts. In the expansion of the blank the strand portions are subjected to a two-fold displacement operation, that is to say, they are bent outward relatively to one another so as to extend 80 divergently from the common bond and they are also pushed back into the central longitudinal plane of the web, in short, flattened. These operations are accomplished by moving 85 the flanges of the blank relatively outward and at the same time applying pressure to the offset bond providing portions to move them and the strands back into the central longitudinal plane of the web. By pressing the offset bond providing portions back toward the central longitudinal plane of the web while the flanges are being spread, the rate at which the bond providing portions are pressed back being proportional to the 90 rate at which the flanges are spread or slightly greater, further stretching of the strands is avoided and at the same time all liability of tearing the strands in the directions of the slits is avoided. The flattening of the displaced parts may be effected by 95 various means, the drawings illustrating for this purpose a series of rolls 8, 9, 10, 11 and 12 by which the operation is completed in successive stages. The relative outward movement of the flanges may be effected by 100 various means but is preferably effected by the spreader plate 13 which is employed in co-operation with the rolls 8, 9, 10 and 11, the web passing over the plate 13 which is 105 thus used as a support and the flattening rolls engaging the displaced parts of the web from above. The plate 13 has a close fit between the flanges 1 of the blank and its sides are regularly divergent whereby said plate 110 increases from a width correspond- 115

120

125

130

ing to that of the web at the end of the strand stretching operation to the width which it is intended that the web shall have in the finished beam, the diverging sides of the plate 5 13 acting on the flanges 1 during the travel of the blank to cause an increase in the mutual spacing of said flanges corresponding to the regular increase in the width of the spreader. The operation of the first of the 10 flattening rolls is illustrated in Figures 19, 20 and 21 from which it will be observed that the roll 8 has applied pressure to the adjacent portion 103 and forced the same to a lower plane, the flanges 1 have been 15 moved relatively outward to a slight degree by the spreader 13 and the strand portions 102 have adjusted or accommodated themselves to the altered positions of the portion 103 and the flanges 1, the laterally adjacent 20 strand portions now extending from the portion 103 at a slight angle to one another and the longitudinally opposite strand portions now extending from the portion 103 at an increased angle to one another. The operation 25 of the second flattening roll 9 is similarly illustrated in Figures 22, 23 and 24 from which it will be observed that the portion 103 has been forced to a position somewhat below that of Figure 21, the mutual 30 spacing of the flanges 1 has been further increased and that the strand portions have again and in like manner adjusted or accommodated themselves to the further altered 35 positions of the portion 103 and the flanges 1. The operation of the third flattening roll 10 is illustrated in Figures 25, 26 and 27 and that of the fourth flattening roll 11 in Figures 28, 29 and 30. These operations are 40 similar to those of the rolls 8 and 9 and involve further increases in the spacing of the flanges 1 and further flattening of the stretched displaced portions.

The fifth and final stage of the expanding operation is performed by a pair of co-operating rolls 12. The spreader 13 projects for some distance in advance of the fourth flattening roll 11 and as the blank is fed forward from this roll a further increase in the spacing of the flanges 1 is effected by the spreader. 45 The rolls 12 act on the blank as it passes beyond the spreader. At this time the flanges 1 have been spaced to the extent determined upon and the flattening of the stretched displaced portions has been nearly completed. 50 The office of the rolls 12 is, therefore, to perform the final step of bringing the displaced portions uniformly into the central longitudinal plane of the web and to give a desirable finish to the completed beam. These rolls are 55 therefore shaped and proportioned to act on all parts of the web and are operative to deliver the completed structural member which is shown in Figures 32 and 33.

It will of course be understood that the 60 number of stages in which the expanding

operation may be performed may be varied and that the indication of five stages in the drawings is merely by way of example.

The process described results in a finished product which is a beam expanded from a 70 rolled structural shape in which all of the parts displaced by the expansion lie in the central longitudinal plane of the beam, the structure being integral throughout. In the completed product the strands 102 α are of 75 equal thickness throughout their extent, the intermediate bonds 103 α are of equal thickness with the strands and the outer bonds 104 α are of somewhat greater thickness than the strands since they are not subject to any 80 stretching and therefore give a greater factor of safety to the structural member.

The above description assumes the production of a lattice truss where the blank has at least three rows of slits but fundamentally 85 the same method can be used for the production of a beam in the form of a Warren truss. In this case the blank is of regular I cross section and, as shown in Figure 34, has two rows of longitudinal slits 106 and 90 107, those of one row in break-joint relation to those of the other row. Between the ends of the slits 106 are portions 108 which provide bonds between the struts and the chord at one side of the beam and between the ends 95 of the slits 107 are portions 109 which provide bonds between the struts and the chord at the opposite side of the beam. The strand portions 110 are delimited by the overlapping 100 portions of the slits 106 and 107 and lie between each pair of adjacent bond providing portions 108 and 109. In the stretching operation each strand portion is bent into substantial V form, the stretching pressure being applied centrally of its length in the same 105 manner in which it is applied to the bond providing portions 103 of the blank used for the lattice truss. The blank at the completion 110 of the stretching operation is shown in Figure 35. The expansion of the blank is carried out in the manner previously described, that is to say the spacing of the flanges is regularly increased to the extent 115 determined upon and the bent and stretched strand portions by pressure applied to their apices are simultaneously and at a proportionate rate pressed back into the central longitudinal plane of the beam. The completed structural member is shown in Figures 36 and 37 in which the strands are indicated at 110 α , the bonds at one side at 108 α and those at the other side at 109 α , the strands being of uniform thickness throughout and the bonds (which are not stretched) being of somewhat greater thickness than the strands 120 125 and therefore giving the beam a factor of safety.

Having fully described my invention, I claim:

1. The method of producing an expanded 130

structural member from a rolled shape, heated to suitable temperature and slit to provide strand portions, which consists in positively displacing the strand portions without altering their lateral angles or the spacing of the bonds which form the connection between the strands and the chords, thereby to stretch said strand portions, and then expanding the shape by altering the lateral angles of the stretched strand portions and simultaneously so positively displacing them as substantially to avoid further stretching.

2. The method of producing an expanded structural member from a rolled shape, heated to suitable temperature and slit to provide strand portions, which consists in positively displacing parts of the shape in which said strand portions are included into substantial V form without altering their lateral angles, thereby to stretch said strand portions, and increasing the width of the shape and progressively with the increase in width positively flattening the displaced parts, thereby substantially to avoid further stretching of the strand portions.

3. In the method of producing an expanded structural member from a rolled shape, heated to suitable temperature, slitting the shape to provide strand portions, preliminarily deforming the strand portions into sinuous outline, thereby to increase their over-all length and cause them to be of uniform thickness from end to end, and then displacing the strand portions without altering their lateral angles, thereby to further stretch them.

4. In the method of producing an expanded structural member from a rolled shape, heated to suitable temperature, slitting the shape to provide strand portions, preliminarily deforming the strand portions to stretch them and to cause them to be of uniform thickness and substantially uniform density from end to end, and then displacing the strand portions without altering their lateral angles, thereby to further stretch them.

5. In the method of producing an expanded structural member from a rolled shape heated to suitable temperature, slitting the shape to provide strand portions, preliminarily deforming the strand portions to stretch them and to cause them to be of uniform thickness and substantially uniform density from end to end, and then further stretching the strand portions.

6. The method of producing an expanded structural member in the form of a lattice truss from a rolled shape, heated to suitable temperature and slit to provide strand portions and at least one row of intermediate bond providing portions which consists in positively displacing and thereby stretching into substantial V form those parts of the shape which are each composed of strand portions and an intermediate bond portion to which the strand portions are connected

without altering the lateral angles of the stretched parts while maintaining the shape at its original width and then expanding the shape by increasing its width to alter the lateral angles of the stretched strand portions and at a proportionate rate positively altering the angles of the strand portions produced by their previous displacement in a manner substantially to prevent further stretching of the strand portions.

7. The method of producing an expanded structural member in the form of a lattice truss from a rolled shape, heated to suitable temperature, which consists in slitting the shape to provide strand portions and at least one row of intermediate bond providing portions, preliminarily deforming the strand portions to stretch them and to cause them to be of uniform thickness and substantially uniform density from end to end, then displacing and further stretching those parts of the shape which are each composed of strand portions and an intermediate bond portion to which the strand portions are connected while maintaining the shape at its original width and then expanding the shape by increasing its width to alter the lateral angles of the stretched strand portions and at a proportionate rate altering the angles of the strand portions produced by their previous displacement in a manner substantially to prevent further stretching of the strand portions.

8. The method of producing an expanded structural member from a rolled shape, heated to suitable temperature, which consists in performing during a continuous movement of the shape the operations of slitting the shape to provide strand portions, preliminarily deforming the strand portions to stretch them and to cause them to be of uniform thickness and substantially uniform density from end to end, then displacing the strand portions without altering their lateral angles, thereby to further stretch them, and then expanding the shape by altering the lateral angles of the strand portions and simultaneously so displacing them as substantially to avoid further stretching.

9. The method of expanding a ribbed metallic structure provisionally slit between and substantially parallel to the ribs, which consists in holding the ribs against relative movement while transversely corrugating the structure between the ribs to lengthen the resultant struts and then expanding the slit portion of the structure.

In testimony whereof I affix my signature.
HARVEY M. GERSMAN.
